UNITED STATES PATENT OFFICE.

EGBERT H. DERBY, OF WINNEBAGO, MINNESOTA.

WRENCH.

No. 857,163.

Specification of Letters Patent.

Patented June 18, 1907.

Application filed August 11, 1906. Serial No. 330,251.

To all whom it may concern:

Be it known that I, EGBERT H. DERBY, a citizen of the United States, residing at Winnebago, in the county of Faribault and State of Minnesota, have invented a new and useful Wrench; and I do hereby declare the following to be a full, clear, and exact description of the invention, such as will enable others skilled in the art to which it appertains to make and use the same.

The invention relates to improvement in wrenches, and has for its object to provide a wrench having V-shaped integral, or alligator jaws, mounted on a pivot, and a spring-actuated dog, for engaging ratchet teeth, on said wrench, whereby the head containing the jaws, may be set at various angles, for engaging nuts or pipes of difficult accessibility.

The invention consists in the novel construction and arrangement of parts herein-after described and illustrated in the drawings, and particularly pointed out in the appended claims.

Figure 1 is a side elevation of a wrench constructed in accordance with this invention. Fig. 2 is a plan view. Fig. 3 is a view similar to Fig. 2, showing a modification.

Referring to the drawing, 1 designates the handle of the wrench, to which is secured plates 2 and 3, which are designed to hold a spring-actuated dog. The spring-actuated dog is mounted in a slot in the handle and is beveled at its outer end whereby it is enabled to engage the teeth 5 of the wrench-head 6, and hold it at the desired adjustment. The wrench head is pivotally mounted on a heavy rivet, 7 which pierces both plates and the handle. The wrench head is preferably alligator or V-shaped, and is provided with teeth or serrations on one of the jaws. The dog 8 which operates in a slot in the handle, between the two plates, is held in engage-

ment with the ratchet teeth 5 by means of a spring 9. When it is desired to release the wrench-head from the spring-actuated dog, a projecting lug 10 is pressed against the spring, and the dog then releases the pivoted wrench-head, which enables the same to be set at another angle.

In Fig. 3 of the drawing, a modification is shown, which shows the plate 2 with transverse slots 11 and 12. The slot 12 admits of a slight oscillation, of the plate 2 when it is desired to lock the dog in engagement with the wrench-head 6, as will be readily understood.

What I claim is,

1. A wrench having a slotted handle, plates mounted on each side of said handle, a V-shaped wrench head pivoted between one of said plates and the handle, a spring-actuated dog mounted in said slot, and adapted to hold said wrench head at the desired adjustment, said plates being adapted to form a housing for said dog, substantially as described.

2. In a wrench, the combination with a movable head pivoted to a handle, a dog mounted in said handle, and having a spring for holding the same in engagement with the head, plates mounted on each side of said handle, and adapted to guide said dog in its movements, one of said plates being slotted and capable of oscillatory motion, said dog having a lug projecting through said slot, for releasing said dog, said slot being L-shaped for the purpose of locking said dog in engagement with said head.

In testimony whereof I have signed my name to this specification in the presence of two subscribing witnesses.

EGBERT H. DERBY.
